TIMING MECHANISM

Edward J. Lauterbur, Sidney, and Frank X. Lauterbur, deceased, late of Sidney, Ohio, by Wilhelmina S. Lauterbur, executrix, Sidney, Ohio

Application September 22, 1933, Serial No. 690,588
Renewed September 10, 1936

5 Claims. (Cl. 200—38)

The invention relates broadly to a time-mechanism for the control of a series of motors or circuits by a single or by a multiple series of time mechanisms each of which come in to action to control a motor or a circuit at a predetermined time and for a period of time, whose length is also predetermined, and this constitutes the primary object of the invention.

It is also possible by the system to control a two speed motor operating a single mechanism or series thereof, so as to run the motor at a slow speed for a predetermined length of time, then at the end of said period, increase the speed for a predetermined length of time.

15 The objects of the invention will be more fully set forth hereinafter or will be apparent to one skilled in the art upon reading the following specifications in which there is set forth an exemplary embodiment comprising two time mechanisms set up in accordance with the invention. Reference is made to the drawing which forms a part hereof, and which shows a time control system in accordance with the invention, in which the time control mechanism is of the spring operated clock type, though any type of self-starting electric clock mechanism may be substituted with proper changes in the means for starting the succeeding electric time control unit. The employment of a mercury 20 tube or similar type of switch, which would start into action the succeeding time control mechanism when desired is exemplary of modifications which may be made in the invention without departing from the spirit thereof.

30 35 The purpose of the timer mechanism in the embodiment shown is completely to control the operation of a standard high speed mixer without attention from the operator. The circuits are arranged to include the motor, a two-speed automatic starter which may be either of the consequent pole or double wound type, push button safety cut-out switches and the timer itself.

Reference is now made to the drawing which forms a part of the specification, it being understood that the showing in the drawing is a preferred form, and that numerous other forms of time mechanisms may be used.

In the drawing:

Figure 1 is a plan view with parts in section 50 of one form of timing mechanism.

Figure 2 is a vertical section with a portion broken away, of one form of timing mechanism taken on the section line 2—2 of Fig. 1.

Figure 3 is a front elevation of one form of 55 timing mechanism.

There is shown in the drawing a time control mechanism of the spring clock type. There is shown at 8 a spring clock mechanism capable of such setting by the key or pointer 30, that at a predetermined time it will operate a shaft 5 9 upon which is mounted a switch operating lever 10. When it is desired to start the system into operation, the clock mechanism 8 is set by means of the pointer 30 for the duration of the period of time, as indicated on the dial 31, required for the first operation.

In the practice of the invention as shown in the drawing, there is employed two time control mechanisms each arranged to operate a switch or series of switches whereby electric circuits are made or broken. It is to be understood that the two mechanisms 8 and 12 are practically identical, and therefore like parts bear like reference numerals. A mechanical or other connection is arranged between the time control 15 mechanisms so that at the end of the cycle of the first to operate, the second is set in motion whereby a predetermined cycle of operations may be controlled by it following that cycle which was controlled by the first mechanism. 20 There are certain advantages inherent in providing two or more mechanisms among which may be mentioned the fact that an operation may be omitted by omitting to set the particular time control mechanism which governs the 25 cycle of the said operation; a series of time control mechanisms are set for different operations which makes the setting less complicated than would be the case if a cycle mechanism were set to control a plurality of operations; the settings, being made upon different time control mechanisms, are properly indicated thereon and may be checked up during the operation of the mechanism; finally, time control mechanisms governing the operation of succeeding cycles 30 35 may be set during the following of a preceding cycle.

The timing mechanisms used in the preferred form comprise the main shaft 33 of a timing clock, to which one end of the main spring 45 34 is attached. The other end of this spring 34 is fixed to a standard in the usual manner. There is the usual escapement and train of gears to time the rotation of this main shaft 33. The shaft 33 projects out through the face of the clock and has a pointer or turning portion 30 fastened to it. There is the usual gear 40 journaled rotatably to the shaft 33 which carries the pawl 35. The ratchet part 41 of the winding means is frictionally journaled to the shaft 33 so that when 50 55

the clock is wound by turning the pointer 30, the spring 34 is coiled; and when the pointer 30 is released, this spring 34 rotates the pointer 30 back toward the place from which it started. 5 However, due to the frictional or clutch action of the ratchet in relation to the shaft 33, it is possible to reverse the turn of the pointer 30, and thus the pointer may be placed at any position. The face of the clock has a dial 31 divided off 10 into minutes. From the above description of the workings of the clock, it is apparent that the pointer 30 may be positioned at any point on the dial, and when the pointer 30 is released, the spring 34 will return the pointer to the point marked zero, in timed relation, due to the escapement on the clock. The shaft 33 has an arm 10 fastened to and projecting from it. On the end of this arm is a pin 10a which, with the 15 turning of the shaft, slips into the Y-shaped socket 42 of the toggle or snap switch 36. This, in turn, as the shaft 33 moves further, throws the switch. The placing of this arm and switch is such that with the setting of the clock, the 20 switch is thrown one way, and when the pointer reaches the zero mark on the dial, the switch is thrown back. Thus, when the pointer is set the switch is opened, and when the pointer, after the given time, dependent on the position it has been 25 set in relation to the dial, returns to zero, the switch will be closed. Both the clocks 8 and 12 are exactly the same as described above. The only difference is in the starting mechanism as heretofore stated, both the clocks must be self-starting.

On the shaft 9 of the clock 8, which is the first 30 clock in the progressive series, is a cam 37a, with a flat portion 37. This cam abuts the end 18a of the arm 18, which is pivoted on an outside support and which has an opposite end portion 18b. This portion carries an edge which will be forced 35 between the teeth of one of the gears on the clock 12, and thus will prevent the clock 12 from running, although the pointer 32 is set. The spring 19 prevents the edge 18b from stopping the clock 12 unless the end 18a is depressed by the cam 37a on the shaft of the clock 8. This cam 37a is so arranged on the shaft 33 that the flat portion 40 of the cam 37 will only be presented to the end 18a of the lever 18 when the clock 8 is at the zero position. Therefore, it is apparent that when the clock 8 and the clock 12 are set, the lever prevents the clock 12 from running; and when the pointer on clock 8 has reached zero, 45 besides throwing the switch as heretofore described, it will also move the lever 18 and permit the clock 12 to start. Of course, from the above description it is apparent that the second clock in the series may be made to release a third clock, 50 and so on indefinitely, by the provision of another member 18 between the second and third clocks, and the provision of another cam 37a upon the shaft 33 of the second clock. It will also be apparent that the switch which is thrown by the arm 10 may be a double switch, or may be a 55 number of switches arranged to be thrown by the same arm. The clocks and their parts are not a part of the invention, nor are the switches and their method of operation by the clocks; but the trigger or lever 18, which is thrown, and which releases the succeeding clock, is the very gist of the invention.

Figure 1 of the drawing shows the two clocks 70 8 and 12 with the dials set at some indicia, and

since the clock 8 is not at zero, the clock 12 is not permitted to move. The effect of this construction is that the clock 12 (the succeeding clock) is not permitted to start until the first 5 clock 8 has run its given or set length of time and the switch has been thrown. Projecting pins 38 may be provided, against which the ends of the pointers of the keys 30 and 32 abut, so that the different clocks will stop as soon as their switches, etc., have been thrown. 10

The setting of clock mechanism 8 closes circuits 2 and 7 of the electrical circuit and leaves circuits 3 and 4 open. A second spring operated clock mechanism 12 is now set for the time duration of the second operation by means of the 15 pointer 32 and dial 31a. The setting of the second time control unit 12, closes the circuits 5 and 6 and at the end of the time duration as set on the clock 12, the circuits 5 and 6 are opened 20 and the circuits 14 and 15 are closed.

Having thus described the invention, what is claimed as new and desired to secure by Letters Patent, is:

1. In a cyclical controlling mechanism, a plurality of time mechanisms arranged in sequence, and capable of being independently set for a predetermined cycle of operation, each of said time mechanisms having controlling means, means impinging on the mechanism of the succeeding time mechanism so as to prevent its starting, and means on the preceding time mechanism to remove said impinging means from the succeeding mechanism at the completion of the cycle of the preceding time mechanism. 25

2. In a cyclical controlling mechanism, a preceding and succeeding self starting time mechanism capable of being independently set for a predetermined cycle of operation, each of said time mechanisms having controlling means, a pivoted lever, one end of which impinges on the mechanism of the succeeding time mechanism and prevents it from starting, means on the preceding time mechanism to rock said lever when said preceding time mechanism has completed its cycle, said rocking of said lever releasing the 40 mechanism of said succeeding time mechanism so that it will start on its cycle of operation. 45

3. In a cyclical controlling mechanism, a preceding and succeeding self starting time mechanism capable of being independently set for a predetermined cycle of operation, each of said time mechanisms having controlling means, a pivoted lever, one end of which impinges on the mechanism of the succeeding time mechanism and prevents it from starting, the other end of 50 the pivoted lever resiliently forced against a circular cam having a flattened portion positioned on the shaft of the preceding time mechanism, the flattened portion of said circular cam being so positioned in regard to the shaft of the 55 preceding time mechanism that it will present itself to the lever end when the cycle of operation of the time mechanism has been completed, whereby the completion of the cycle of operation of the preceding time mechanism will 60 permit the lever to move and release the mechanism of the succeeding time mechanism, and thus permit it to start.

4. In a cyclical controlling mechanism, a preceding and succeeding time mechanism comprising self starting clock mechanisms capable of being set for a predetermined time of running, switches operated by said clock mechanisms when their predetermined time of running has 70 been completed, removable means for preventing 75

the starting of the succeeding clock mechanism when the preceding clock mechanism is running, means on the preceding clock mechanism for removing aforesaid means from said succeeding 5 clock mechanism when said preceding clock mechanism is stopped.

5. In a cyclical controlling mechanism, a preceding and succeeding self starting time mechanism capable of being independently set for 10 a predetermined time of running, each of said time mechanisms having controlling means,

means connecting said time mechanisms and actuated by said preceding time mechanism to prevent said succeeding time mechanism from running when said preceding time mechanism is running. 5
